UNITED STATES PATENT OFFICE.

CHARLES R. LION, OF LOS ANGELES, CALIFORNIA.

AUTOMATIC SEWER FLUSHER.

Application filed June 20, 1927. Serial No. 200,034.

My invention pertains to automatic sewer flushers of the type in which a flushing appliance is set in a manhole and connected to a sewer to periodically discharge the desired 5 quantity of flushing water.

In installing the automatic flushers the contractor building the manhole or the sewer, or both where they are made in the same general construction, fits a frame in 10 the manhole construction upon which the flushing apparatus is installed. As the frame frequently is not level, it entails considerable difficulty in leveling the floor of the flushing device when installing same.

15 An object of my invention is a simple construction of floor connection to the frame so that the floor may be properly leveled so that the flushing mechanism may operate properly. In the type of flushing mechanism with which my floor is generally connected it is necessary that the operating devices, such as a rod connected to a tilting pan and a bell valve, operate in vertical 20 lines to prevent binding or the like and to 25 allow proper working of the flushing apparatus.

My invention may be considered as an improvement on that of Garrie H. Burns #1,256,656, issued February 19, 1918. The 30 particular improvement in the floor comprises using a T-shaped frame which is built into the masonry of the manhole, or the well connected therewith. The platform, which preferably has an upper surface of wood, 35 is adjusted by adjusting screws which engage an internal flange of the frame and may be utilized to adjust the floor in a horizontal position.

My invention is illustrated in the accompanying drawings, in which:

Figure 1 is a vertical section through a manhole and sewer well illustrating my floor construction with the general type of flushing device set forth in the above noted 45 patent.

Figure 2 is a horizontal section on the line 2—2 of Fig. 1 giving the plan view of the floor.

Figure 3 is a vertical transverse section 50 on the line 3—3 of Fig. 2 in the direction of the arrows.

In the drawings the well is indicated by the numeral 1, being connected to sewers 2 and 3, or if the sewers are of large size the well may be connected to an opening in the 55 top of same. The manhole structure is des-

ignated by the numeral 4 and the framing 5 is built in the masonry at the top of the well. This frame is of T-shape and is usually constructed with a relatively wide flange 60 6 extending into the masonry, a narrow flange 7 extending outwardly, and a web 8 positioned vertically and substantially in the line of the wall of the manhole or well.

The floor construction is constructed substantially as follows:

A floor board 10 forms the base for supporting the flushing mechanism, hereunder described, and preferably has a pair of straps 11 of non-corrodible metal secured on the under surface at each end or each side and held to the board by bolts 12 or other suitable securing means. The board is provided with a series of openings 13 and adjusting bolts 14 are secured through the straps or bars 11 with the heads of the bolts fitting in the openings 13. The lower end of these bolts engage the inwardly projecting flange 7 of the frame 5. In practice I find that four bolts are sufficient to properly level the floor and after it is properly leveled the openings 13 in the floor boards are filled with some suitable composition indicated by the numeral 15, for which I find melted sulphur satisfactory. The peripheral edge 85 16 of the board around the web 8 of the frame is also filled with a suitable composition such as sulphur or the like, thus making a water tight joint between the board and the frame and also embedding the heads of 90 the adjusting nuts 14.

In the type of flusher illustrated a flushing column 17 is secured to the floor board, this column being tubular and having a pan operating rod 18 extending therethrough, 95 this being connected to the pan 19 which is pivotally connected by an arm 20 to a bracket 21 bolted to the bottom of the floor. A lever 22 connected by a swivel rod 23 to the pan operating rod actuates the stem 24 of the bell valve 25 which seats on a valve seat 26. The stem 24 is guided in a supporting arm 27 and the lever is pivoted on an upper arm 28, both of these arms extending laterally from the column.

In order that the flushing mechanism may work properly it is necessary that the floor be level so that the flushing column 17 will occupy a vertical position, and the pan operating rod and the stem 24 move in a vertical direction, thus preventing binding and unnecessary friction in the operation. As

the flusher is operated due to water filling in the manhole and overflowing the flushing column into the pan causing the pan to dump and thereby raise the valve bell, it is necessary to eliminate friction as much as possible. Hence the above construction for leveling the floor simplifies the installation and maintenance of the automatic sewer flushers of the type set forth.

10 It is to be understood, however, that my invention may be applied to flushers of other types.

Various changes may be made in the principles of my invention without departing 15 from the spirit thereof, as set forth in the description, drawing and claims.

I claim:

1. In a sewer flusher, a frame having an internal flange, a floor having straps secured 20 thereto on the under surface, adjusting bolts extending through said straps and resting on the flange, and a flushing mechanism on the floor.

2. In a sewer flusher, an inverted T- 25 shaped frame, a floor having a plurality of

straps secured on its under surface, bolts threaded through said straps, the bolt heads fitting in openings in the floor, the ends of the bolts bearing on one of the flanges of the frame, means forming a tight seal at the 30 bolts and between the floor and the frame, and a flusher mounted on the floor.

3. A sewer flusher comprising in combination, a manhole having a well, an inverted T-shaped frame having lateral flanges and 35 a vertical web, the outer flange being embedded in the manhole walls, the inner flange extending inwardly, a floor having a plurality of straps secured on its under surface, bolts threaded through said straps bearing 40 on the inner flange, there being openings in the floor for the bolt heads, packing material in said openings surrounding the bolts and surrounding the periphery of the floor between same and the web of the frame, and 45 flushing apparatus mounted on the floor.

In testimony whereof I have signed my name to this specification.

CHARLES R. LION.
